(57) **CLAIM**

The ornamental design for a hair claw clip, as shown and described.

DESCRIPTION

FIG. 1 is a front, top, and left perspective view of a hair claw clip showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a rear, bottom, and right perspective view thereof. The broken lines shown in the drawings depict portions of the hair claw clip that form no part of the claimed design.
